UNITED STATES PATENT OFFICE.

WILLIAM F. RESCHKE, OF WICHITA, KANSAS.

ATTACHMENT FOR LISTER-CULTIVATORS.

1,253,529.

Specification of Letters Patent. Patented Jan. 15, 1918.

Application filed August 20, 1917. Serial No. 187,183.

To all whom it may concern:

Be it known that I, WILLIAM F. RESCHKE, a citizen of the United States, residing at Wichita, in the county of Sedgwick and State of Kansas, have invented certain new and useful Improvements in Attachments for Lister-Cultivators; and I do declare the following to be a full, clear, and exact description of the invention, such as will enable others skilled in the art to which it appertains to make and use the same.

My invention has for its principal object to provide a simply constructed and inexpensive arrangement of parts whereby any of the well known types of lister cultivators, may be easily converted for use as "ridge busters", that is for the purpose of cultivating the ridges as well as the furrows. Another object of the invention is to so mount the cultivator disks as to permit them to be easily adjusted by a hand lever or the like, so that they may be made to draw a greater or less amount of earth from the ridges.

Yet another object is to so construct the adjusting means of the disks, as to permit said means to be easily secured to and operated by the transverse rock shaft which is usually employed for raising and lowering the shovels.

With the foregoing general objects in view, the invention resides in the novel features of construction and unique combinations of parts to be hereinafter fully described and claimed, the descriptive matter being supplemented by the accompanying drawings which form a part of this specification and in which:

Figure 1 is a top plan view showing one of the improved attachments applied to a portion of a lister cultivator;

Fig. 2 is a rear elevation of Fig. 1; and

Fig. 3 is a longitudinal section on substantially the plane indicated by the line 3-3 of Fig. 1.

In the drawings above briefly described, the numeral 1 designates a portion of the connecting bar which usually extends between the two halves or units of lister cultivators which are constructed for operating upon two rows simultaneously. By means of the arm 2 or any other suitable device, the bracket 3 on the rear end of the tongue 4, is swiveled to the bar 1, a transverse tubular frame member 5 being hinged at 6 to the bracket 3 for vertical swinging, said frame member carrying the usual standards 7 upon

whose lower ends the furrow wheels 8 are rotatably mounted. Passing through the tubular frame member 5, is a rock shaft 9 having squared ends, it being upon said ends that the shovels are usually mounted. When applying the present invention, however, these shovels are omitted, but the adjusting lever 10 of the shaft 9 and the rack 11 thereof, are retained since other parts are operated from the shaft 9 and the latter must therefore be held in adjusted position.

The construction so far briefly described may be found in a number of well known types of lister cultivators which operate upon the bell crank principle, that is by swinging the wheels 8 upwardly and downwardly to respectively lower or raise the cultivator disks. In the present showing, this swinging of the wheels 8 is accomplished by means of a lever 12 which is fulcrumed to the tongue 4 and connected by means of suitable links or the like 13 with the axles of the wheels 8. It is to be understood that this adjustment constitutes no part of the present invention, but that it, as well as the features above described, are shown only for the purpose of illustrating the application of the improved features.

The usual disk carrying means are detached from the frame member 5 and an inclined hanger or arm 14 is secured thereto between the standards 7, the upper end of said arm having a right angular seat 15 which receives the similarly shaped frame member 5, pivotally connected bolts 16 being provided for passage around the remainder of the member 5 for the purpose of securing it rigidly in the seat. The lower end of the arm 14 is preferably widened and provided with a pair of toothed bosses 17 with which similarly toothed plates 18 on a pair of vertically disposed bearings 19 coact, bolts or the like 20 being provided for securing said plates to the bosses, so that the bearings 20 may be adjusted from the vertical, whenever occasion should demand.

Pivotedly connected with the lower or rear end of the arm 14, by means of vertical studs 21 which are received in the bearings 20, are two horizontally swinging shafts 22, said shafts carrying the usual or any preferred type of cultivator disks 23 which are mounted rotatably thereon. At 24, a pair of links 25 are pivoted to the shafts 22, the front ends of said links being similarly connected with crank arms 26, said arms

having guides 27 and set screws 28 for securing them on the squared ends of the shaft 9, so that turning of said shaft, by means of the lever 10, will swing the shafts 5 22 forwardly and rearwardly to vary the angular relation of the disks 23, whereupon the latter are caused to move a greater or less amount of earth. In most types of the invention, one of the crank arms 26, in addition to the guides 27 and screws 28, will be equipped with a channel shaped arm 29 by means of which the lever 10 is attached thereto. In other cases, however, in which the lever is permanently secured to the shaft 15 9 it is unnecessary to provide the arm 29.

By constructing the attachment as or substantially as above described, it may be easily and inexpensively manufactured and marketed, yet will be attachable to practically all types of lister cultivators, thus making it possible to convert the comparatively light cultivators into substantial "ridge busters." One machine may thus be used for the two purposes, so that expense 25 is greatly decreased. On account of these advantages, the specific features of construction shown and described, constitute the preferred form of the attachment. I wish it understood, however, that within the scope 30 of the invention as claimed, numerous minor changes may well be made.

I claim:

1. In a lister cultivator, the combination 35 of a transverse rockable frame member and means for rocking it, a pair of spaced standards depending rigidly from said frame member and wheels on the lower ends of said standards, a single inclined arm secured rigidly at its upper end to said frame member between said standards, the lower end of 40 said arm being disposed centrally in rear

of said wheels and having a pair of substantially vertical bearings, a pair of transverse disk-carrying shafts pivoted at their inner ends to said bearings for horizontal swinging, links extending forwardly from 45 said shafts, crank arms to which said links are connected, a transverse rock shaft adjacent said frame member and carrying said crank arms, and means for rocking said shaft. 50

2. An attachment for lister cultivators comprising an inclined arm widened horizontally at its upper and lower ends and having at said upper end a transversely extending L-shaped seat to receive a transverse frame member of the cultivator, means coacting with said seat for rigidly securing said arm to said frame member, the lower end of said arm being disposed in a vertical 55 transverse plane and having horizontally spaced bosses whose rear sides are toothed, a pair of plates having teeth engaging the teeth of said bosses, bolts connecting said plates and bosses to permit turning of the former, substantially vertical bearings formed on the outer edge portions of said plates, a pair of transverse disk-carrying shafts whose inner ends are pivoted to said 60 bearings for horizontal swinging, and links 65 extending forwardly from said shafts and having crank arms at their front ends for mounting on a transverse rock shaft of the cultivator. 70

In testimony whereof I have hereunto set 75 my hand in the presence of two subscribing witnesses.

WILLIAM F. RESCHKE.
